ATTORNEY

UNITED STATES PATENT OFFICE.

SOLOMON MARKS, OF CINCINNATI, OHIO, ASSIGNOR OF ONE-HALF TO
WILLIAM PRIOR KING, OF LUDLOW, KENTUCKY.

HUB-BAND.

SPECIFICATION forming part of Letters Patent No. 350,259, dated October 5, 1886.

Application filed March 30, 1886. Serial No. 197,227. (No model.)

To all whom it may concern:

Be it known that I, SOLOMON MARKS, of Cincinnati, Hamilton county, Ohio, have invented certain new and useful Improvements 5 in Bands for Vehicle-Hubs, of which the following is a full, clear, and exact specification, reference being had to the accompanying drawings, forming a part thereof, in which—

Figure 1 is a perspective view of my hub-10 band. Fig. 2 is a perspective view of my ornamental lining. Fig. 3 is a perspective view of my hub-band and lining in position, looking from the rear. Fig. 4 is a perspective view of my hub-band and lining, with a part of the 15 lining broken away, in position looking from the front. Fig. 5 is a vertical section of my hub-band and lining on the line X X in Fig. 3.

The same letters refer to the same parts throughout the several drawings.

20 My invention relates to improvements in hub-bands and ornamental linings.

My invention consists of, first, a metallic hub-band, A, adapted to fit on the outer ends of vehicle-hubs, having at or about its center 25 three or more internal lugs or shoulders, *a a a*, each having the slot *d*; second, the metallic lining B, adapted to fit snugly into the outer end of the hub-band A, said lining B having the cap *b*, adapted to fit over the outer end of the 30 hub-band, and having the inward projection *b'*, with the prongs or lugs *b''*, and then bent again at right angles, as shown in Fig. 2.

My invention is operated by placing the metallic lining B inside the hub-band A, so

that the inward projection *b'* rests upon the 35 lugs or shoulders *a a a*, and the clamps or lugs *b'' b'' b''* pass through the slots *d d d* in said lugs *a a a*. Then by crimping the prongs or lugs *b b b* against the back of the lugs *a a a*, as shown in Figs. 3 and 5, the lining B is 40 securely held in its proper position, and the cap *b* is closed firmly over the outer edge of the hub-band.

Having thus fully described my invention, what I claim as new therein, and desire to secure by Letters Patent, is—

1. A hub-band having on its inner surface lugs with slots, in combination with an ornamental lining having lugs or prongs adapted to hold said lining securely in said hub-band, 45 substantially as shown and described.

2. A hub-band, A, having on its inner surface lugs *a a a*, with slots *d d d*, in combination with an ornamental lining, B, having the cap *b*, adapted to fit over the outer edge of the 50 hub-band A, the inward projection *b'*, having the lugs or prongs *b'' b'' b''*, adapted to fit into the slots *d d d* of the lugs *a a a*, and to be crimped on the back of said lugs, substantially as shown and described.

60 The foregoing specification of my invention signed by me this 27th day of March, A. D. 1886.

SOLOMON MARKS.
